UNITED STATES PATENT OFFICE.

CHARLES P. WETMORE, OF MILWAUKEE, WISCONSIN, ASSIGNOR TO DURANT MANUFACTURING COMPANY, OF MILWAUKEE, WISCONSIN, A CORPORATION OF WISCONSIN.

DRIVE FOR COUNTERS.

1,261,081.

Specification of Letters Patent.

Patented Apr. 2, 1918.

Application filed August 10, 1916. Serial No. 114,126.

To all whom it may concern:

Be it known that I, CHARLES P. WETMORE, a citizen of the United States, and resident of Milwaukee, in the county of Milwaukee,

5 and State of Wisconsin, have invented new and useful Improvements in Drives for Counters, of which the following is a description, reference being had to the accompanying drawings, which are a part of this

10 specification.

The invention relates to counters which are adapted to record a series of operations or for counting different commodities and their weight and for numerous other pur-
15 poses where a count is necessary.

The invention is particularly designed to provide a simple positive and accurate driving mechanism for the counter which consists of a ratchet on the shaft carrying the
20 counters, a Geneva toothed gear for engaging the ratchet, and a pawl coöoperating with the gear to prevent the counter moving more than one tooth during each operation of the driving mechanism.

25 In counters of this kind the restraining pawl is generally operated by a spring and as the spring will not keep its initial tension its employment destroys the positive action of the device and this positive accurate action
30 is essential as sometimes one movement of the counting wheel will indicate that a great quantity of material has been weighed as in the case of recording the quantity of grain delivered to an elevator where every
35 movement of the counting wheel represents the receipt of a hundred bushels. It will therefore be seen that the dispensing with the unreliable spring for actuating the pawl and its replacement by means for posi-
40 tively actuating the pawl is of decided advantage and I have accomplished this object by providing a cam for operating the pawl on the operation of the counter.

The invention further consists in the several features hereinafter described and more particularly defined by claims at the conclusion hereof.

In the drawings:

Figure 1 is a plan view of a device em-
50 bodying the invention;

Fig. 2 is a section taken on the line 2—2
of Fig. 1;

Fig. 3 is a section taken on the line 3—3
of Fig. 1.

55 The driving mechanism for the counter

comprises an operating shaft 4 journaled in a frame 5 and a driving connection between said shaft and the counter shaft 6 also journaled in a frame.

The counter shaft is of usual construction 60 as is also the counter wheel 7 which is operatively connected to a ratchet or gear wheel 8 mounted on the shaft 6. The ratchet wheel 8 may be directly connected up to the wheel 7 in any well-known manner and this 65 connection may also embody any suitable means for resetting the counter, said means not being shown as it does not constitute any part of the present invention. As many counting wheels may be mounted on the 70 shaft 6 as desired and these may be operatively connected to each other in any suitable manner. As the subject matter of this invention resides in the means for driving the counter shaft 6 irrespective of the number 75 of counting wheels mounted thereon and the way they are connected together I have shown only one counting wheel which may be the only one used or the first of a series of counting wheels mounted on the counter 80 shaft 6.

The means for actuating the shaft 6 comprises a driving connection between said shaft and the drive shaft 4 and means for insuring but one movement of the shaft 6 for a 85 single operation of the drive shaft 4.

This driving connection consists of a member 9 having a single Geneva tooth 10 formed thereon which is adapted to mesh with the teeth 11 on the ratchet wheel 8. 90 While the shaft 4 may be either rotated or oscillated to cause the tooth 10 to advance the ratchet wheel a single tooth to move the wheel 7 for a single count I have shown a means for oscillating the shaft 4 which 95 is used in connection with restraining means hereinafter described. This means for oscillating the shaft 4 comprises a crank 12 which is adapted to move the shaft 4 in one direction and a retractile spring 13 mounted 100 on said shaft and secured at one end to the frame 5 and at the other to a stop finger 14 mounted on the shaft 4. The movement of the shaft 4 is limited by stops 15 and 16 projecting upwardly from the base and into 105 the path of movement of the stop finger 14. With this construction the crank is moved up by the operator, through any suitable connection, to cause the tooth 10 to engage one of the teeth 11 of the ratchet 8 to there- 110

by move the counter shaft for one count and the shaft 4 is then returned to its initial position through the agency of the spring 13.

The gear member 9 is of peculiar form in 5 that the periphery 17 is circular and its diameter is such that a portion of the periphery will lie between two of the teeth 11 of the ratchet 8 as shown in Fig. 3 and this will prevent forward or backward movement 10 of the ratchet so that the gear member forms a means for preventing movement of the ratchet.

The single tooth 10 will engage the ratchet wheel 8 to move said wheel for a single 15 count of the counter wheel 7 and on the return movement of the shaft 4 the tooth 10 moves over the inclined face 18 of the next tooth and assumes a position behind it as shown in Fig. 3 to move this next tooth 20 forwardly on the next operation of the counter. On the return movement of the tooth 10 the ratchet would be moved backwardly the same distance were it not for the restraining means now to be described.

25 The means for restraining the movement of the counter shaft after it has been moved to effect one count consists of a pawl 19 pivotally mounted on a pin 20 secured to the frame 5. The front end 21 of this pawl 30 has an inclined face 22 adapted to move between the ratchet teeth 11 and to contact with the inclined face 23 of the tooth to limit the backward movement of the ratchet wheel to prevent back movement thereof to 35 the position previously occupied thereby.

As previously stated I have provided positively operating means for actuating the pawl and this consists of a pin 24 secured to the gear member 9 and adapted to contact with cam surfaces 25 and 26 formed 40 near the rear end of the pawl.

The operation of the pawl is as follows: On a forward movement of the counter wheel through movement of the counter 45 wheel through the gearing connection previously described, the shaft 4 is moved to cause the pin 24 to move along the cam surfaces 25 and 26 and then away from the same to a position shown in Fig. 2 the pawl 50 moving over the inclined face 18 of the ratchet tooth adjacent thereto and finally moving off said face. On the return movement of the shaft the pin 24 engages the

cam surface 26 and moves the front end of the pawl downwardly against the face 23 of the next tooth and then moves along the cam surface 25 so as to positively lock the pawl in engagement with the ratchet and thus insure an accurate count.

While I have shown and described a positively operated pawl which is actuated in conjunction with an oscillatory shaft, it will be understood that the gearing connection between the drive shaft and the counter shaft may also be employed in connection 65 with devices in which the drive shaft is rotated and in which other means are provided for insuring against the backward movement of the shaft 6 and its counting wheel 7.

70 The invention thus exemplifies a simple and efficient counter-actuating mechanism.

What I claim as my invention is:

1. In a counter, the combination, with a 75 counter shaft provided with a counter-wheel, of means for moving said shaft comprising a ratchet wheel mounted thereon, an actuating shaft, a member mounted on said actuating shaft and provided with a single tooth adapted to mesh with any tooth of the ratchet wheel, a pivoted pawl for engaging the ratchet to prevent backward movement of the counter shaft, and having a cam surface thereon, and means for positively actuating the pawl comprising a pin on the single toothed member for engaging said cam surface.

2. In a counter, the combination, with a 80 counter-shaft provided with a counter-wheel, of means for moving said shaft comprising a ratchet wheel mounted on the shaft, an actuating shaft, a member mounted on said actuating shaft and provided with a single tooth adapted to mesh with any tooth of the ratchet wheel, and having a portion adapted 85 to be disposed between two adjacent teeth of the ratchet wheel to prevent movement of the ratchet wheel after it has been moved by said single tooth, and means for limiting the backward movement of said counter-shaft to prevent back movement thereof to a 90 position previously occupied thereby.

95 100 In testimony whereof, I affix my signature.

CHARLES P. WETMORE.
